UNITED STATES PATENT OFFICE

CHARLES A. ERTOLA, OF SAN FRANCISCO, CALIFORNIA

DISPENSING DEVICE

Application filed December 17, 1929. Serial No. 414,728.

My invention relates to improvements in dispensing devices for tube contained products wherein rollers are mounted in opposing relation upon the front and back of a body and held in firm frictional contact with said body and a tube mounted upon said body for pressing the product outwardly from the tube.

The primary object of my invention is to provide an improved device for dispensing the contents from collapsible metal tubes.

Another object is to provide an improved dispensing device which will facilitate the expelling of plastic products from collapsible containers.

A further object is to provide an improved device wherein pressure is applied from the closed end of a collapsible tube to dispense a product therefrom, the product being fully and efficiently expelled from the tube.

Another object is to provide an improved dispensing device which is light and compact and upon which a collapsible tube of a product to be dispensed may be readily attached and detached as desired.

A further object is to provide an improved device of the character described which can be economically manufactured and which is durable and efficient.

I accomplish these and other objects by means of the improved device disclosed in the drawings forming a part of the present application wherein like characters of reference are used to designate similar parts throughout the specification and drawings, and in which—

Fig. 1 is a front elevation of my improved dispensing device with a collapsible tube of a product to be dispensed mounted thereon; Fig. 2 is a side elevation of the device as shown in Fig. 1;

Fig. 3 is a side elevation of the device after a portion of the contents of the tube have been dispensed;

Fig. 4 is a sectional view of the device taken upon the line 4—4 of Fig. 3 in the direction indicated and showing the manner in which the tube is collapsed; and

Fig. 5 is a broken detail view, drawn upon an enlarged scale, as showing the manner in

which the closed end of the tube is engaged.

Referring to the drawings, the numeral 1 is used to designate in general a body, preferably formed from suitable sheet metal. The body 1 is provided with flanges 2 along the longitudinal edges thereof, and rearwardly offset mounting bracket portions 3 are formed at the ends to engage and hold the body in spaced relation to a wall or other suitable supporting surfaces. An opening 4 is preferably formed in the upper bracket portion 3 whereby the body may be suspended upon a screw or other suitable supporting member, not shown.

A pair of tube engaging lugs 6 are struck outwardly from the body adjacent the upper end thereof. The lugs are preferably arranged to extend over the clamp member 7 commonly applied upon the closed end of a collapsible tube 8 of the ordinary and well known form, said lugs preferably having sufficient resiliency to grip and effectually hold said closed end of the tube. A shouldered bead 9 is preferably formed along the free ends of the lugs 6 to seat the edges of the clamp member 7 of a tube and prevent said member 7 and the end of the tube from being forced downwardly out of engagement with the lugs. An annular band 11 is preferably mounted upon the body adjacent the lower end thereof to receive the tube and hold said tube in proximate parallel relation to the body.

A pair of rollers 12 and 13 are mounted in opposing relation upon the front and back of the body 1. The back roller 13 is received between the flanges 2 and engages the back surface of the body 1. The front roller 12 extends the full width of the body 1. Spring members 14 are mounted at the ends of the rollers 12 and 13, said members 14 being provided with bearing portions 16 rotatably engaging the ends of shafts 17 extending axially through the rollers. The springs 14 normally exert a pressure holding the rollers in firm frictional engagement with the front and back of the body 1. A knob 18 is secured upon an outwardly extending end of the shaft 17 of one of the rollers whereby said roller may be rotated and both rollers moved longi-

tudinally along the body 1. A pair of gears 19 may also be mounted if desired upon the shafts 17 in meshing relation to impart rotation from one of the rollers to the other.

5 Hooks 21 are preferably struck from the body 1 adjacent the lower end thereof to receive a tooth brush 22 or other object to be used with the product dispensed.

- In operation, the rollers 12 and 13 are 10 moved to the extreme top of the body 1, and a tube 8 of a product to be dispensed is mounted upon the body 1 by inserting the closed end of the tube under the lugs 6, the outlet end of the tube being inserted through the band 11. 15 When the rollers are rotated in the directions indicated by the arrows in Figs. 2 and 3 of the drawings, said rollers, being held in frictional engagement with the front and back of the body 1 by means of the spring members 14, will be rolled downwardly past the lugs 6 and the outer roller 12 will be moved to engage the closed end of the tube 8.

When it is desired to dispense a portion of the contents of the tube 8, the usual cap 24 25 screwed onto the dispensing tip 25 of the tube is removed, and the knob 18 turned in the direction indicated in Fig. 2, thereby rolling the outer roller downwardly onto the tube 8 and imposing a pressure sufficient to expel 30 a portion of the contents from the tube. As the roller 12 is moved downwardly, the roller 13 is moved a corresponding amount so that the rollers will bear upon opposite sides of the body and cause the tube to be pressed flat 35 against the front of the body 1, as shown in Fig. 3, thereby completely expelling the contents of the tube downwardly toward the dispensing outlet. As the contents of the tube are displaced entirely by pressure applied 40 from the closed end of the tube, the unemptied portion of the tube will be kept expanded to its full symmetrical size, thereby presenting a neat appearance and preventing the unsightly distortion commonly 45 encountered. After the desired amount of the product has been dispensed, the cap 24 is screwed onto the tip 25 to retain the remaining product within the tube.

50 My improved device is particularly useful for dispensing dentifrices, and in this connection, the hooks 21 afford a convenient means for hanging tooth-brushes 22 upon the body 1.

55 While I have illustrated and described only one specific structure of my improved dispensing device, the details of construction are of course subject to modification in numerous ways without departing from the spirit of my invention, and I therefore desire to avail myself of all modifications in structure and arrangement which may fall within the scope of the appended claims.

Having thus described my invention what 60 I claim as new and desire to secure by Letters Patent is—

1. A dispensing device for tube contained products comprising a body; means for detachably securing a collapsible tube upon the front of the body; and a pair of rollers mounted upon the body in opposing relation upon the front and back, said rollers being movable into engagement with the tube from the closed end thereof and with the body, respectively, to dispense the contents of the tube outwardly therefrom. 70

2. A dispensing device for tube contained products comprising a body; means for detachably securing a collapsible tube upon the front of the body; a pair of rollers mounted upon the body in opposing relation upon the front and back, said rollers being movable into engagement with the tube from the closed end thereof, and with the body, respectively, to dispense the contents of the tube outwardly therefrom; and means for holding the rollers in firm frictional contact with the body and tube. 80

3. A dispensing device for tube contained products comprising a body; means for detachably securing a collapsible tube upon the front of the body; a pair of rollers mounted upon the body in opposing relation upon the front and back, said rollers being movable into engagement with the tube from the closed end thereof and with the body, respectively, to dispense the contents of the tube outwardly therefrom; and means for imparting rotation from one of said rollers to the other. 90

4. A dispensing device for tube contained products comprising a body; means for detachably securing a collapsible tube upon the front of the body; a pair of rollers mounted upon the body in opposing relation upon the front and back, said rollers being movable into engagement with the tube from the closed end thereof and with the body, respectively, to dispense the contents of the tube outwardly therefrom, and gears mounted adjacent the ends of the rollers in meshing relation to impart rotation from one roller to the other. 100

5. A dispensing device for tube contained products comprising a body; means for detachably securing a collapsible tube upon the front of the body; a pair of rollers mounted upon the body in opposing relation upon the front and back, said rollers being movable into engagement with the tube from the closed end thereof and with the body, respectively, to dispense the contents of the tube outwardly therefrom; gears mounted adjacent the ends of the rollers in meshing relation to impart rotation from one roller to the other and resilient means mounted 115 in connection with the rollers and pressing said rollers together to retain the gears in meshing relation and to hold the rollers in frictional engagement with the body and tube. 120

6. A dispensing device for tube contained products comprising a body; means for detachably securing a collapsible tube upon the front of the body; a pair of rollers mounted in opposing relation upon the front and back of the body; a pair of spring members mounted in connection with the ends of the rollers to resiliently hold the same in frictional engagement with the body and tube; and a knob mounted upon one end of one of the rollers for rolling the rollers along the body to dispense the contents from the tube. 10
7. A dispensing device for tube contained products comprising a body; means for detachably securing a collapsible tube upon the front of the body, a pair of rollers mounted in opposing relation upon the front and back of the body; a pair of spring members mounted in connection with the ends of the rollers to resiliently hold the same in frictional engagement with the body and tube; a knob mounted upon one end of one of the rollers for rolling the rollers along the body to dispense the contents from the tube; and gears mounted in meshing relation upon the ends of the rollers for imparting rotation from one roller to the other. 15
8. A dispensing device for tube contained products comprising a body provided with mounting brackets formed at the ends thereof and rearwardly offset to hold the body in spaced relation to a supporting surface; tube engaging lugs struck from the body to detachably engage the closed end of a collapsible tube and support said tube upon the front of the body; a pair of rollers mounted in opposing relation across the front and back of the body; resilient means holding the rollers in contact with the body and tube; and means for rolling the rollers along the body to engage the tube and press the contents therefrom. 20
9. A dispensing device for tube contained products comprising a body provided with mounting brackets formed at the ends thereof and rearwardly offset to hold the body in spaced relation to a supporting surface; tube engaging lugs struck from the body to detachably engage the closed end of a collapsible tube and support said tube upon the front of the body; a pair of rollers mounted in opposing relation across the front and back of the body; resilient means holding the rollers in contact with the body and tube; means for rolling the rollers along the body to engage the tube and press the contents therefrom; and a band mounted upon the body to detachably engage the tube adjacent the dispensing end thereof. 25
10. A dispensing device for tube contained products comprising a body provided with mounting brackets formed at the ends thereof and rearwardly offset to hold the body in spaced relation to a supporting surface; tube engaging lugs struck from the body to 30
- detachably engage the closed end of a collapsible tube and support said tube upon the front of the body; a pair of rollers mounted in opposing relation across the front and back of the body; resilient means holding the rollers in contact with the body and tube; means for rolling the rollers along the body to engage the tube and press the contents therefrom; and hooks struck from the body to support objects to be used with the dispensed product. 35
11. A dispensing device for tube contained products comprising a body provided with mounting brackets formed at the ends thereof and rearwardly offset to hold the body in spaced relation to a supporting surface; tube engaging lugs struck from the body to detachably engage the closed end of a collapsible tube and support said tube upon the front of the body; a pair of rollers mounted in opposing relation across the front and back of the body; resilient means holding the rollers in contact with the body and tube; means for rolling the rollers along the body to engage the tube and press the contents therefrom; and gears mounted upon the ends of the rollers to impart rotation from one roller to the other. 40
- In witness whereof, I hereunto set my signature. 45
